(57) **CLAIM**

The ornamental design for a set of storage cubby inserts, as shown and described.

DESCRIPTION

FIG. 1 is a front perspective view illustrating a set of storage cubby inserts design;

FIG. 2 is a front view illustrating a set of storage cubby inserts design;

FIG. 3 is a back view illustrating a set of storage cubby inserts design;

FIG. 4 is a side view illustrating a set of storage cubby inserts design according to one embodiment;

FIG. 5 is another side view illustrating a set of storage cubby inserts design;

FIG. 6 is a top view illustrating a set of storage cubby inserts design;

FIG. 7 is a bottom view illustrating a set of storage cubby inserts design; and,

FIG. 8 is an environmental view illustrating a set of storage cubby inserts design.

The broken lines showing the cabinet in FIG. 8 are included for the purpose of illustrating environment and forms no part of the claimed design.
